UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CORRUGATED METALLIC PLATE FOR RAILWAY CARS.

Application filed May 16, 1925. Serial No. 30,777.

My invention relates to the construction of railway cars having parts formed of metallic plates which are subjected to lateral, buckling and sometimes torsional stresses. 5 Said parts are made of one or more metallic plates or panels formed with vertical or horizontal corrugations or other integral stiffening or bracing means to resist such stresses. While efforts are made to block the lading 10 in the car, the shocks caused by the heavy locomotives, the emergency air brake and the classification hump tear the lading away from its moorings and throw it against the end of the car, the lateral weaving of the 15 car throws it against the side of the car, and the impact throws it against the bottom of the car. My invention is adaptable to several parts of a railway car such as side doors, side walls, floor sheets (sloping or otherwise), hopper doors, roof sheets, etc., but it is especially adaptable for use as the end wall of a railway car and is also adaptable to box, gondola or other types of cars.

One of the objects of the invention is to 25 provide metallic parts of a railway car which have great strength to resist the torsional and weaving stresses which exist in a railway car when moving in service. These stresses are caused by the inertia of the roof and superstructure when the train is suddenly stopped; rough or uneven track; the superelevation of the track on curves; the lateral inertia in rounding curves; eccentric thrust due to the lading being secured to one 35 side of the car; the cars being "cornered"; the use of push pole pockets, etc. Such stresses rack and distort the superstructure which decreases the life of the car, and also causes the car to leak grain, sand, and other 40 such material. Furthermore, such stresses cause leaky roofs and leaky and inoperative side and end doors.

The tendency of an all metal end wall to 45 bulge is resisted partially by the corrugations, stiffening members or whatever means have been provided to transmit such stresses to the side wall or frame members of the car. Such tendency is also resisted by the corner post of the car acting as a vertical 50 beam supported at its top and bottom and sustaining a horizontal load; in other words, the bulging of the end would pull the opposite corner posts toward each other. This bulging also tends to pull the end (or side) 55 plate downwardly and the end (or side) still

upwardly. Another object of the invention is to reinforce the frame members against thrust perpendicular to their length by means forming a part of a corrugated or otherwise reinforced metallic end wall. 60

In the drawings:

Fig. 20 is a section on line 20—20 of Fig. 10.

It has been proposed to press the central portion of a metallic plate (or plates) so as 95 to form a continuous web or flange surrounding a panel and to reinforce this panel by horizontal corrugations or other integral reinforcements which traverse the panel and terminate adjacent the opposite portions of the web or flange. In such an arrangement the load upon the horizontal corrugations is transmitted to the continuous web or flange only through the intermediate means of the flat portion of the plate lying between the 100 end of the horizontal corrugations and continuous web, or flange. It has also been proposed to press the central portion of a metal plate (or plates) so as to form a web or flange (supposedly) surrounding a panel and 105 110

to reinforce this panel by horizontal corrugations or other integral reinforcements which are the same depth as the web or flange where they merge into it. In such an arrangement the web or flange as a beam is destroyed. In my construction the transverse corrugations destroy only a part of the value of the web, leaving a remaining portion which extends continuously around the panel to receive the stresses from the horizontal corrugations and to function as a beam and a stiffener. Such stresses are transmitted directly to the remaining portion of the web.

15 The corner post of an ordinary box or gondola car performs two functions; first, as a compression member of the truss forming the side frame of the car, and, secondly, as a vertical beam receiving the loads from the several horizontal frame members of the end wall and transmitting them to the side wall of the car. The end plate of a car is the end member of the roof framing structure and the end sill is the end member of the underframe and as such performs similar functions to the corner post. Also the end plate and the end sill are horizontal beams receiving the loads from the end wall and transmitting them to the roof structure and underframe, respectively. Therefore, in the specification and in the claims forming a part thereof the term "frame member" means either the corner post, end plate, end sill, side plate, side sill or any other similar frame member.

In my construction the transverse corrugations receive the impact thrust of the shifting load and transmit them to the surrounding corrugation which is preferably positioned adjacent the frame member or members. This surrounding corrugation may be designed to reinforce the existing frame member of a car or to cooperate with another part of the car to perform the functions of the frame member or may be designed to independently perform the functions of the frame member and thus constitute the frame member itself.

In my construction the central portion of the metallic plate 1 (or plates 1-2) is pressed to form a continuous corrugation 3 surrounding a panel 4, which corrugation comprises an inner wall 5-6 and an outer wall 7-8 and is preferably positioned adjacent the outside edges of the plate or outside edges of the wall whether the wall is made of one or more plates.

The panel 4 is reinforced with corrugations 9 or integral ribs which traverse the panel and merge into a part of the opposite portions 5-5 of the inner wall of the continuous corrugation, leaving a remaining portion 10 of the inner wall which extends continuously and uninterruptedly on three (or preferably four) sides of the panel.

The inner wall 5 receives the load from the transverse corrugations 9 and in combination with the outer wall 7 of the continuous corrugation forms a beam or a stiffener to prevent bulging in transmitting the load from the transverse corrugations to the car. The inner walls 5 and outer walls 7 of the vertical portion of the continuous corrugation are prevented from buckling or deflecting by being connected to the horizontal portions 6-8 of the corrugations by the (preferably) radial portions 11-12 which thus form a continuous or unending corrugation.

The transverse corrugations may be made the same depth or a greater depth than the depression forming the continuous corrugation but the corrugations are of less depth than the walls 5-5 where they merge into it. The advantages of a continuous web in combination with the corrugations of great depth (and strength) may also be obtained by providing a series or plurality of shallow corrugations 13 adjacent the continuous web which merge into a lesser number of larger and deeper (therefore stronger) corrugations 14 adjacent the middle of the plate. (See Figs. 5-9.) These shallower and deeper corrugations may be so positioned and dimensioned that the length of the center line of the metal of the shallower corrugations (see Fig. 8) is the same as the length of the center line of the metal of the deeper corrugations (see Fig. 6) which is a material manufacturing advantage, as it more evenly distributes the draw and stretch of the metal due to pressing the corrugations in the plate.

Figs. 1-9 inclusive show a construction wherein the surrounding continuous corrugation is positioned adjacent to (and preferably parallel to) the corner post 15, the end plate 16 and/or the end sill 17 and the outer wall 7-8 of the continuous corrugation is extended to form a flange 18-19-20 which is secured to the adjacent frame member so as to reinforce it. The outer walls may be extended as at 21 to join adjacent corrugated plates together. The horizontal portions of the surrounding corrugation furnish an excellent place for the nailing strip 22 for the vertical lining boards 23.

Figs. 10-17 inclusive show a construction wherein the outer walls 7-8 of the surrounding corrugation are extended to form flanges 18-24-25 which are secured to the longitudinal frame members (side plate 26, side sills 27 and/or center sills 28) of the car so as to perform the usual functions of the corner post, end sill, and/or end plate, respectively, thus eliminating the necessity of such members. The saving of these parts reduces the manufacturing cost, necessity of carrying such parts in stock, as well as reducing the weight of the car. The inner

walls 5—6 extend continuously and uninterruptedly on four sides of the wall (even though the end is made of two united plates). The corrugations are shallower 5 where they merge into the continuous corrugation than elsewhere.

Figs. 18-20 inclusive are enlarged cross sections showing in detail the various associated parts of the construction illustrated 10 by Figs. 10-17 inclusive. The usual parts of the car are shown, such as side sheathing 50, side lining 51, side lining nailing strip 52, ridge pole 53, roofing boards 54, and fascia 55, flooring 56 and striking casting 57.

15 While I have shown and described the corrugations positioned horizontally, it is understood that the corrugations may extend vertically or otherwise, and still come within the scope of the invention, and, furthermore, 20 while I have described and claimed the wall made of "a plate," it is understood that it may be made of one or more united plates and still come within the scope of the invention.

25 I claim:

1. A metallic plate pressed to form a continuous corrugation surrounding a panel, said panel formed with transverse corrugations which merge into the opposite portions 30 of the continuous corrugation.

2. A metallic plate pressed to form a continuous corrugation surrounding a panel, said panel formed with transverse corrugations which merge into the opposite portions 35 of the continuous corrugation, said transverse corrugations being of less depth than the continuous corrugation where they merge into it.

3. A metallic plate pressed to form a continuous corrugation surrounding a panel, said panel formed with transverse corrugations which merge into the opposite portions 40 of the continuous corrugation, said transverse corrugations being of less depth than the continuous corrugation where they merge into it but of greater depth adjacent their middle.

4. A metallic plate pressed to form a continuous corrugation adjacent its perimeter surrounding a panel, said panel formed with transverse corrugations which merge into the opposite portions 45 of the continuous corrugation, said transverse corrugations being of less depth than the continuous corrugation where they merge into it.

5. A metallic plate pressed to form a continuous corrugation surrounding a panel, said panel formed with transverse corrugations which merge into the opposite portions 50 of the continuous corrugation and are of less depth than the continuous corrugation where they merge into it, the outer wall of said continuous corrugation extended to form a flange.

6. A metallic plate pressed to form a con-

tinuous corrugation surrounding a panel, said panel formed with transverse corrugations which merge into the opposite portions of the continuous corrugation and are of less depth than the continuous corrugation 70 where they merge into it, the outer wall of said continuous corrugation extended to form a flange perpendicular to the plane of the plate.

7. A metallic plate pressed to form a continuous corrugation surrounding a panel, said panel formed with transverse corrugations which merge into the opposite portions of the continuous corrugation and are of less depth than the continuous corrugation 75 where they merge into it, the outer wall of said continuous corrugation extended to form a flange, portions of which are perpendicular to the plane of the plate.

8. A metallic plate pressed to form a continuous corrugation surrounding a panel, said panel formed with transverse corrugations which merge into the opposite portions of the continuous corrugation, said transverse corrugations merging together to form 80 a lesser number of corrugations adjacent the middle of the plate.

9. A metallic plate pressed to form a continuous corrugation surrounding a panel, said panel formed with transverse corrugations which merge into the opposite portions of the continuous corrugation, and are of less depth than the continuous corrugation 95 where they merge into it, said transverse corrugations merging together to form a 100 lesser number of deeper corrugations adjacent the middle of the plate.

10. A metallic plate pressed to form a continuous corrugation surrounding a panel, said panel formed with transverse corrugations which merge into the opposite portions of the continuous corrugation, said transverse corrugations merging together to form a lesser number of deeper corrugations adjacent the middle of the plate, the length of 105 the center line of the metal of the shallower transverse corrugations being substantially the same as the length of the center line of the metal of the deeper transverse corrugations.

11. A metallic plate pressed to form a continuous corrugation surrounding a panel, said panel formed with transverse corrugations which merge into the opposite portions of the continuous corrugation and are of less depth than the continuous corrugation 115 where they merge into it, said transverse corrugations merging together to form a lesser number of deeper corrugations adjacent the middle of the plate, the length of the center line of the metal of the shallower 120 transverse corrugations being substantially the same as the length of the center line of the metal of the deeper transverse corrugations.

GARTH G. GILPIN.
